UNITED STATES PATENT OFFICE

2,611,297

MEANS FOR LOCKING FIREARM BARRELS

Clarence E. Simpson, Wilbraham, Mass., assignor
to the United States of America as represented
by the Secretary of War

Original application June 7, 1946, Serial No.
675,124. Divided and this application Decem-
ber 21, 1949, Serial No. 134,311

2 Claims. (Cl. 89—14)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to semiautomatic firearms having a recoiling barrel and is particularly directed to improved means for rapid barrel replacement.

This application is a division of my copending application for Firearm dated June 7, 1946, Serial No. 675,124 and now matured into U. S. Patent No. 2,555,379.

Most firearms of the semiautomatic type which utilize a comparatively large caliber cartridge are of rather ponderous and complicated construction. Accordingly, it is of the utmost importance that such a firearm be relatively simple to disassemble into unit assemblies for ease in transportation. This requirement for simplicity of disassembly is also of particular importance in the problem of barrel replacement.

Accordingly, it is an object of this invention to provide in a large caliber semiautomatic weapon an improved construction which will permit easy and rapid replacement of the barrel.

It is a further object of this invention to provide a large caliber military type of firearm which is so constructed that it can be rapidly and easily disassembled into two major assemblies for ease in transportation.

The specific nature of the invention as well as other objects and advantages thereof will clearly appear from a description of a preferred embodiment as shown in the accompanying drawings in which:

Fig. 1 is a left side perspective view showing the barrel and barrel extension assembled in the receiver with the feedway in the locked position.

Fig. 2 is a view similar to Fig. 1 but showing the barrel and barrel extension partially retracted from their battery position and with the feedway in the unlocked position.

Fig. 3 is a view similar to Figs. 1 and 2 but showing the barrel and barrel extension about to be disengaged from the receiver and showing in dotted outline the pivoting movement imparted to the barrel upon such disengagement.

Fig. 4 is a perspective fragmentary view of the left and right side plates comprising the receiver.

Fig. 5 is a rear end elevational view of the barrel and barrel extension.

Fig. 6 is a left side view of the barrel extension.

Fig. 7 is a top view of the rear portion of the

2

firearm with the feedway in the unlocked position and the breech block partially retracted.

Fig. 8 is a right side elevational view of the forward portion of the firearm showing the front barrel bearing and the recoil mechanism latch in cross section.

Fig. 9 is a cross-sectional view of the barrel sleeve taken along the line 9—9 in Fig. 8.

The semiautomatic weapon to which the present invention applies is a heavy large caliber gun designed specifically for attacking armored vehicles such as tanks or the like.

As illustrated in the drawings, there is provided an open receiver 5 comprising a bottom plate 6 and a left and right side plate designated respectively by numerals 7 and 8. A breech block assembly comprising a breech block 9 and a carrier 75 is slidably mounted in receiver 5 for longitudinal reciprocal movement between a recoiled and a counter-recoiled battery position. In the latter position, locking lugs (not shown) on breech block 9 are arranged to engage in front of similar locking lugs 10 provided at the rear end of a substantially rectangular barrel extension 13. A barrel 12 is threadably secured at its breech end to barrel extension 13. A pair of longitudinal ribs 14 are provided on opposite sides of barrel extension 13 and are arranged to slidably engage in longitudinal grooves 15 extending along the interior walls of side plates 7 and 8. The forward portion of each of grooves 15 terminates in a recess 16 formed by cutting away a portion of the interior wall of side plates 7 and 8 and is best illustrated in Fig. 4. Recesses 16 permit disassembly of barrel extension 13 from receiver 5 in a manner to be described.

A rectangular bar 17 is slidably mounted to left side plate 7 by means of a screw 18 which passes through an elongated slot 19 provided in bar 17 and threadably engages in side plate 7. A washer 20 of greater diameter than screw 18 serves as a bearing surface for the head portion of such screw. A latch 21 is pivotally secured to the forward end of bar 17 and is provided with an inwardly extending lug 22. During counter-recoil movement of barrel extension 13, a stud 23 protruding from the left side thereof is arranged to contact the rear surface of lug 22 and thereby carry bar 17 forward as barrel 12 and barrel extension 13 move into battery position. The front edge of lug 22 is provided with an angular cam surface 24 arranged to mate with a similarly inclined surface 25 on the rear of stud 23 so that latch 21 can be pivoted out from in front thereof to permit rearward movement of barrel

extension 13 during assembly thereof into receiver 5. Resilient means, preferably in the form of a flat leaf spring 26, normally biases lug 22 into its stud engaging position.

Side plate 1 is provided with a fixed bracket 27 and side plate 8 is provided with an oppositely disposed hinge portion 70. Bracket 27 is cut away along its length as shown at 71 in Fig. 2 to form a substantially keyhole-shaped opening. A transverse feedway 28 is pivotally secured to hinge portion 70 by means of pin 72 and releasably secured to bracket 27 by means of pin 29. Pin 29 differs from pin 72 in that the central section thereof is slabbed on one side as shown at 73 in Fig. 7 so that when such pin is rotated by means of a short rod 31 inserted through the head thereof, slab portion 73 is permitted to pass through opening 71 and allow feedway 28 to be pivoted about hinge pin 72. A semicircular cut 30 on the bottom of feedway 28 provides access for the breech end of barrel 12. Rearwardly of and adjacent to cut 30, a rectangular opening 11 permits similar access for barrel extension 13. Consequently, barrel 12 and extension 13 cannot be removed from receiver 5 until feedway 28 is unlocked from bracket 27 on left hand side plate 7 and pivoted to the position shown in Figs. 2 and 3.

Beneath barrel 12 there is provided a cylindrical tube 32 housing a recoil mechanism, the operation and function of which is fully disclosed in U. S. Patent No. 2,364,103 dated December 5, 1944. Fixedly secured to the front end of tube 32, as by threads 33, is a front barrel bearing 34 having an upwardly extending loop portion 35. Barrel 12 is arranged to be slidably insertable through an axial opening 36 provided through loop portion 35. The upper wall surface of opening 36 is tapered forwardly as shown at 37 in Fig. 8 for a distance slightly greater than half the length thereof so as to form a slightly larger opening at the rear of loop portion 35 than at the end of the taper. The lower wall surface of opening 36 is similarly tapered as shown at 38 but in a direction opposite that of taper 37. Hence, barrel 12 can be tilted and appreciable amount from the horizontal in order to facilitate removal from and insertion through loop portion 35. Yet when barrel 12 is properly assembled, as will be later described, the horizontal wall portions of opening 36 are of sufficient length to serve as an adequate bearing support for barrel 12.

A spacer 39 is suitably secured between the front ends of side plates 1 and 8 and is provided with a longitudinal hole 40 through which cylindrical tube 32 is arranged to extend. Spacer 39 is also provided with a vertical hole 42 which extends upwardly therethrough so as to intersect longitudinal hole 40. Hole 42 is threaded along a portion thereof as shown at 43 in Fig. 8 and is arranged to receive a hollow screw 44. The hollow interior of screw 44 is counterbored as shown at 45 and a latch 46 is inserted therethrough. Latch 46 comprises a cylindrical stem portion 47 and a head portion 48 from the top of which protrudes a lug 49. A hydraulic cylinder 50 in tube 32 is provided with a reduced diameter portion forming a shoulder 51 which is arranged to be engaged by lug 49. A lever 52 is pivotally secured to the lower end of stem portion 47 as by a pin 53. A spring 54 surrounds stem portion 47 and is seated in the counterbored portion 45 of screw 44 so as to exert an upward bias against head portion 48 of latch 46. A stud 55 projects from the side of head portion 48 and slidably engages a

vertical slot 56 provided in the rear wall of vertical hole 42 in order to prevent rotation of latch 46 and thereby of lever 52 pinned thereto. By depressing lever 52, lug 49 is withdrawn from in front of shoulder 51 and thereby allows cylinder 50 to move forwardly for a purpose to be shown. A handle 69 is suitably secured to the rear end of tube 32 and provides means whereby the entire recoil mechanism can be manually moved forwardly.

A cylindrical sleeve 57 is suitably secured to barrel 12 and an integral fork 58 extends downwardly therefrom and is arranged to engage in an annular groove 59 provided in a piston rod 60 which extends rearwardly out of cylinder 50. Rod 60 is operatively connected to mechanism (not shown) for providing counter-recoil movement to breech block 9. Within cylindrical tube 32 there is provided an operating spring 68 arranged to bias cylinder 50 forwardly and another spring 74 arranged to bias barrel 12 forwardly.

In order to manually retract breech block 9, there is provided an operating slide 61 to which is connected a length of chain 62 having a retracting handle 63 at the end thereof. Slide 61 is slidably secured to left hand side plate 7 and fixedly secured to carrier 75 by suitable means (not shown). A trigger mechanism 64 is suitably secured to right hand side plate 8 and attached thereto is a length of chain 65 to the end of which is secured a pin 66. Right hand side plate 8 is also provided with a transverse hole 67 into which pin 66 is arranged to be inserted as shown in Fig. 7. Thus there is provided means for retaining breech block 9 and carrier 75 in a partially re-coiled position so as to permit disassembly of barrel 12.

Before disassembly is started, the recoiling parts of the firearm should be in the battery position of Fig. 1. Then by grasping retracting handle 63 with the left hand and breech block 9 with the right, the latter can be retracted to the position shown in Fig. 2. Hence, barrel extension 13 which is locked to breech block 9 will also be retracted and will move rearwardly out from under rectangular opening 11 in feedway 28. While holding breech block 9 and carrier 75 in this retracted position with the right hand, the left hand can be used to rotate pin 29 and pivot feedway 28 outwardly from its previous horizontal position over barrel 12.

Upon release of breech block 9, the recoiling parts move forwardly under the tension of operating springs 68 and 74 until halted by contact of stud 23 on barrel extension 13 with lug 22 on latch 21. Then by releasing a catch 76 which latches breech block 9 to carrier 75, rearward movement of carrier 75 by means of handle 63 on slide 61 will cause breech block 9 to disengage from barrel extension 13 as fully explained in the aforementioned U. S. Patent No. 2,555,379. Breech block 9 is then retracted sufficiently to permit pin 66 to be inserted into hole 67 of slide plate 8 and thereby hold breech block 9 and carrier 75 in the position shown in Fig. 7. Thereupon latch 21 is manually pivoted to withdraw lug 22 from in front of barrel extension 13 allowing barrel 12 and barrel extension 13 to move forwardly until fork 58 contacts the rear end of hydraulic cylinder 50.

The next step required is to pivot lever 52 downwardly as shown in Fig. 3 in order to withdraw lug 49 on latch 46 from in front of shoulder 51 in hydraulic cylinder 50. Thereupon barrel 12 and barrel extension 13 can be pushed forwardly

until ribs 14 on barrel extension 13 clear longitudinal grooves 15 in side plates 7 and 8 and align with recesses 16. Thereupon, barrel extension 13 can be lifted upwardly to tilt barrel 12 and disengage fork 58 from piston rod 60. Tapered portions 37 and 38 in loop 35 of front barrel bearing 34 permits the pivoting movement shown by the dotted lines in Fig. 3. Barrel 12 can then be withdrawn entirely from bearing 34.

To reassemble the barrel or replace it with another, barrel extension 13 is first attached thereto and then placed on the top surfaces of side plates 7 and 8 slightly to the rear of recesses 16. In this position, fork 58 will engage piston rod 60 which had been previously moved slightly to the rear due to the bias of operating spring 68. Then by pushing barrel extension 13 forwardly, its weight will cause ribs 14 to drop into recesses 16 and align with longitudinal grooves 15. Then by merely reversing the procedure outlined above, barrel 12 can be readily assembled to receiver 5 and retained therein against disassembly by feedway 28.

Thus there is here provided a construction in which the barrel 12 and barrel extension 13 can be readily removed from the rest of the gun for transportation purposes. Reassembly of the parts into operating position is also accomplished as readily and simply as the disassembly.

I claim:

1. In a firearm, the combination of a channel-shaped receiver having a longitudinal groove in either side thereof, a substantially rectangular barrel extension having a longitudinal rib on either side thereof for slidable engagement with said respective receiver groove, each of said grooves terminating at the forward end thereof in a cutaway portion of sufficient length to permit vertical passage therethrough of said barrel extension rib, a barrel fixedly secured to said barrel extension for movement therewith, a cylindrical tube extending through the front of said receiver and disposed beneath and parallel to said barrel, a spring-biased piston slidably mounted for longitudinal reciprocal movement in said tube, yoke means connecting said barrel with the rear end of said piston whereby the spring-urged movement thereof imparts counter-recoil movement to said barrel and barrel extension, a blocking member pivotally secured at one end to one side of said receiver adjacent the rear end of said cutaway portion therein and releasably latched at the other end to the opposite side of said receiver, said blocking member having an arcuate underside portion and a rearwardly adjacent rectangular recessed portion, a shoulder formed by the junction of said underside portions of said blocking member, said arcuate underside portion arranged to fit around the upper periphery of said barrel and said rectangular recessed portion arranged to provide access for said barrel extension whereby the side of said shoulder serves to stop said barrel extension and thereby said barrel in battery position, means for releasing the latched end of said blocking member from said receiver whereby pivotal movement thereof transversely of said receiver

withdraws said shoulder from in front of said barrel extension thereby permitting said barrel extension to be moved forwardly until said yoke means contacts the rear end of said cylindrical tube, and retractable detent means located at the front end of said receiver for normally engaging said cylindrical tube to prevent forward movement thereof when said blocking member is rendered inoperative, all adapted and arranged whereby retraction of said detent means from engagement with said tube frees said cylindrical tube and thereby said barrel and barrel extension for simultaneous forward movement in order to align said ribs on said barrel extension with said cutaway portions in said receiver for disassembly of said barrel and barrel extension therefrom.

2. The combination defined in claim 1 wherein said cylindrical tube includes a shoulder on the underside thereof and said retractable detent means comprises a hollow screw threadably secured in said receiver adjacent the front end thereof, a cylindrical latch member slidably mounted through said screw for vertical movement into and out of engagement with said shoulder in said tube, a projecting stud on the upper portion of said latch slidably engageable in said receiver for preventing rotation of said latch in said hollow screw, spring means normally biasing said latch upwardly into engagement with said shoulder in said tube, the lower end of said latch extending downwardly out of said receiver, a fixed pin transversely mounted in said lower end of said latch and of such length as to protrude from either side thereof, and a lever loosely engageable with said depending latch end and disposed between the bottom end of said hollow screw and said fixed pin whereby pivotal downward movement of said lever about the ends of said fixed pin as a fulcrum retracts said latch member out of engagement with said shoulder in said cylindrical tube, said hollow screw being arranged to adjust and maintain the clearance between the upper end of said latch and the underside of said cylindrical tube.

CLARENCE E. SIMPSON.
